UNITED STATES PATENT OFFICE.

JOSEPH END, OF BROOKLYN, NEW YORK, ASSIGNOR TO MUTUAL NOVELTY CORPORATION, OF NEW YORK, N. Y., A CORPORATION OF NEW YORK.

DESIGN FOR A DOLL.

Application filed June 4, 1926. Serial No. 17,934. Term of patent 7 years.

To all whom it may concern:

Be it known that I, JOSEPH END, a citizen of the United States of America, residing at Brooklyn, Kings County, State of New York, have invented a new, original, and ornamental Design for a Doll, of which the following is a specification, reference being had to the accompanying drawing, forming part hereof, in which the figure illustrates a perspective view of a doll showing my new design.

I claim—

The ornamental design for a doll as shown.

Signed at New York city this 18th day of May, 1926.

JOSEPH END.
